SELF-LOCKING CONTAINER

Albert St. Arnauld, Detroit, Mich.

Application April 3, 1936, Serial No. 72,526

2 Claims. (Cl. 232—41)

My invention relates to improvements in a self locking container for milk, groceries, and similar materials and it is the principal object of my invention to provide such a container which automatically locks itself upon the disposal of commodities therein so as to prevent subsequent unauthorized removal of the commodities.

It is a further object of my invention to provide improved means for locking such a container against unauthorized entry together with means for unlocking the mechanism.

These improvements are embodied in the mechanism illustrated in the accompanying drawings, in which:—

15 Figure 1 is a side view of my self locking container installed in a house or similar building structure and adjacent a door thereof; Fig. 2, a side view of the self locking container with its door in an open position; Fig. 3, a sectional view 20 of self locking container taken on the line 3—3, Fig. 2, said sectional view disclosing said door in a closed position; Fig. 4, a sectional view of the self locking container taken on the line 4—4, Fig. 3; Fig. 5, a partial sectional view of the self locking container taken on the line 5—5, Fig. 3; Fig. 6, a partial sectional view of the self locking container taken on the line 6—6, Fig. 3; Fig. 7, a partial sectional view of the self locking container taken on the line 7—7, Fig. 6; Fig. 8, a 25 partial plan view of an alternative lock operating mechanism for the container together with a partial horizontal sectional view of the container; Fig. 9, a side view of the lock operating mechanism disclosed in Fig. 8; Fig. 10, an end view of the lock operating mechanism disclosed in Figs. 8 and 9; Fig. 11, a side view of one of the brackets for supporting a treadle crankshaft of the lock operating mechanism disclosed in Figs. 8, 9 and 10; Fig. 12, a plan view of the bracket disclosed 30 in Fig. 11; Fig. 13, an end view of the bracket disclosed in Fig. 11; Fig. 14, a side view of the lock plunger mechanism disclosed in Figs. 8, 9, and 10; Fig. 15, a sectional view of the lock 35 plunger mechanism disclosed in Fig. 14, said sectional view being taken on the line 15—15, Fig. 14; Fig. 16, a plan view of a bracket for supporting one end of the treadle crankshaft of the lock operating mechanism disclosed in Figs. 8, 9 and 10; Fig. 17, a side view of the bracket disclosed 40 in Fig. 16; Fig. 18, a side view of a connecting link of the lock operating mechanism disclosed in Figs. 8, 9 and 10; Fig. 19, an edge view of the connecting link disclosed in Fig. 18; Fig. 20, a front view of a catch member of the lock operating mechanism disclosed in Figs. 8, 9 and 10;

Fig. 21, an end view of the catch member disclosed in Fig. 20; Fig. 22, an end view of the catch member disclosed in Fig. 20; Fig. 23, a side view of one of the brackets for supporting the treadle of the lock operating mechanism disclosed in Figs. 8, 9 and 10; Fig. 24, a bottom view of the bracket disclosed in Fig. 23; Fig. 25, a side view of the pedal crankshaft of the lock operating mechanism disclosed in Figs. 8, 9 and 10.

Similar numerals refer to similar parts 10 throughout the several views.

Figure 1 discloses one of my self locking containers A installed in a building structure 1, such as a residence or similar building structure, to permit such commodities as milk, groceries, or 15 similar goods, to be delivered to the inmates of the residence or similar building structure without danger of having the commodities unlawfully removed or stolen from the self locking container A.

The self locking container A is disclosed as being installed adjacent the casing 2 of the door 3 and positioned above the floor 4 of the porch 5, the construction of the self locking container A, however, permitting its location at any desired height or position relative to the building structure 1.

Also it is to be understood that the self locking container A may be constructed and marketed as an accessory unit or it may be constructed as an 30 integral part of a building structure, as desired.

The self locking container A is provided with the side walls 6 and 7, the bottom wall or floor 8, the upper wall 9, together with the outside door 10 and the inside door 11.

The outside door 10 is connected to and supported from the side wall 6 by the hinges 12, the outside door 10 being accessible, from the outside of the building structure 1, to permit a milkman, delivery man, or similar operator to place 40 commodities in the self locking container A without bothering the inmates of the building structure 1.

The inside door 11 is connected to and supported from the side wall 6 by the hinges 13, the 45 inside door 11 being accessible, from the interior of the building structure 1, to permit the inmates thereof to remove the commodities, at their convenience, from the self locking container A and without leaving the building structure 1.

The outside doors 11 and 12 may be constructed to extend for the total depth of the self locking container A or they may extend for only a portion of the depth of the self locking container A in which case front and rear walls 14, 15 and 55

18 will be respectively provided, as disclosed in Figs. 2 and 4, with the door openings 16 and 17 therein, Fig. 4 omitting the inside door 11 therefrom.

5 The outside door 10 is provided with the handle or knob 19 and the inside door 11 is provided with the handle or knob 20, said handles or knobs 19 and 20 extending through the doors and being respectively riveted over as at 21 and 22.

10 The outside door 10 is provided with the housing 23 in which is slidably mounted the plunger or catch 24, said plunger or catch 24 being actuated in one direction by the spring or resilient member 25, the plunger or catch 24 being provided 15 with the bevel or angular surface 26 together with the shouldered portion 27 to limit the outward movement of the plunger or catch 24 by suitable engagement with a shouldered portion of the housing 23 which is secured to the outside door 10 20 by the rivets or bolts 28, the plunger or catch 24 being disclosed, in Figs. 6 and 7, in its maximum outward position.

The interior of the self locking container A is divided into the two chambers 29 and 30 by the 25 wall or partition 31.

The treadle or platform 32 is located in the chamber 29 and is pivotally supported on the bottom wall or floor 8 by the hinges 33, the treadle 32 being disclosed in its normal position 30 at the uppermost end of its travel in Fig. 4, the treadle 32 being normally maintained in its uppermost position by the spring or resilient member 34 which is provided with the cylindrical shaped end 35 for slidably engaging the under side of the 35 treadle 32, the spring 34 being provided with a flange 36 which is secured to the bottom wall 8 by the rivets or screws 37.

The treadle 32 is also provided with the bracket 38 which is suitably secured to the underside of the 40 treadle 32 and provides the opening 39 between the bracket 38 and the treadle 32 for receiving the curved end 40 of the crank shaft 41 which is rotatably mounted in the brackets 42 which are secured to the bottom wall 8 by the rivets or 45 screws 43.

The curved end 40 of the crank shaft 41 extends through the opening 39 and is adapted to be moved by the treadle 32 from the position as indicated by the dotted lines 44 in Fig. 2 to the 50 position as indicated by the dotted lines 45 in Fig. 2, the treadle 32 being moved from the position as indicated in Fig. 4 to a lowermost position adjacent the bottom wall 8 of the self locking container A, the curved end 40 tending to slide 55 longitudinally of the space 39 to accommodate pivotal movement of the treadle 32.

As the treadle 32 is moving downwardly to move the curved end 40 of the crank shaft 41 from the position indicated by the dotted lines 44 in Fig. 2 60 to the position indicated by the dotted lines 45, the arm 46 of the crank shaft 41 will move from its position as indicated by the full lines in Fig. 2 to the position as indicated by the dotted lines 47 which will move the rod 48 and cause the bell 65 crank 49 to move from the position as indicated by the full lines in Fig. 6 to the position indicated by the dotted lines 50 in Fig. 6, which will in turn cause the rod 51 to move the latch plate 52 from the position as indicated by the full lines in Fig. 6 70 to the position as indicated by the dotted lines 53 in Fig. 6 and in which position the boss 54 of the latch plate 52 will have been moved upwardly to a position behind the end of the plunger 24 as indicated by the dotted lines 56 in Fig. 6, thus 75 preventing the outside door 10 from being opened

due to the engagement of the boss 54 with the plunger 24.

The arm 46 of the crank shaft 41 is pivotally connected to the rod 48 at 57, the rod 48 being further pivotally connected at 58 to the lower arm 5 of the bell crank 49.

The bell crank 49 is pivotally mounted on the pin or shaft 59 and has its upper arm pivotally connected at 60 to the rod 51, the rod 51 being pivotally connected at 61 to the latch plate 52. 10

The latch plate 52 is provided with the slots 62 for engaging the screws or rivets 62A which are suitably supported in the wall portion 18 of the self locking container A, the screws or rivets 62A thus guiding the latch plate 52 in its movement. 15

The crank shaft 41 is further provided with the bent arm portion 63 which is adapted to engage the bottom wall 8 when the treadle 32 is in its normal and uppermost position, thus insuring that the treadle 32 will not move to a position 20 above that disclosed in Fig. 4.

The outside door 10 is provided with the spring or resilient member 64 which is pivotally connected at 65 to the outside door 10 and at 66 to the inside wall 6, thus causing the outside door 10 25 to tend to always move to its closed position.

It is now to be noted that when the treadle 32 is pivotally moved downwardly from its position as indicated by the full lines 32 to a position substantially parallel with the bottom wall 8, the 30 latch plate 52 will move adjacent and under the plunger 24 to lock the outside door 10 and to prevent its being opened from the outside of the self locking container A and the building structure and to thus operate the treadle 32 in its door 35 locking position, the milk man, delivery man, or similar operator, will place an object on the treadle 32 which by its weight will cause the treadle 32 to move downwardly from its normal position. 40

Figs. 2 and 3 disclose bottles 67 as having been placed on the treadle 32 by the milk man, delivery man or similar operator.

If more than one bottle of milk, such as 67, is to be delivered to the inmate of the building then 45 additional bottles such as 68 or similar commodities may be placed in the compartment 30 after the outside door 10 has been opened, it being always necessary, however, to place at least one bottle 67 or similar unit on the treadle 32 so that 50 when the outside door 10 is closed the lock mechanism of the container A will be automatically operated in its self locking operation.

The inmates of the building structure 1 may readily open the inside door 11 to place empty 55 milk bottles in the chamber 30, the treadle 32, however, being left free of any milk bottles 67 or similar commodities so that the outside door 10 may be opened, it being understood that the operator from the outside of the building will always 60 place one or more of the milk bottles 67 or similar units on the treadle 32 to insure the container A being operated automatically to a self locking position as above described.

Figs. 8, 9 and 10 disclose an alternative construction by means of which a treadle 69 may be utilized for automatically operating the self locking mechanism of my invention.

The treadle 69 is similar to the treadle 32 but is fixedly mounted directly on the crank shaft 70 70 by means of the hinged brackets 71 which are suitably secured to the underside of the treadle 69 by the screws or rivets 72, the brackets 71 being provided with the bosses 73 which are in turn provided with the bores 74 for fitting over the 75

crank shaft 70, the bosses 73 being secured to the crankshaft 70 by the pins 71A.

Figs. 23 and 24 disclose one of the brackets 71 in detail.

5 The crank shaft 70 is pivotally mounted in the bores 75 of the bosses 76 of the brackets 77, one of which is disclosed in detail in Figs. 11, 12 and 13.

10 The brackets 77 are each provided with a flange portion 78 which are adapted to be secured to the bottom wall 8 by the screws 79 extending through suitable openings in the flange portions 78.

15 Also the brackets 77 are each provided with a flange portion 80 which extends upwardly at one side of the flange portion 78, the flange portion 81 having the angularly positioned surface 82 for engaging the upper surface of the treadle 69 to limit it in its maximum uppermost position as disclosed in Fig. 10.

20 The crank shaft 70 is retained longitudinally in the bores 75 of the bosses 76 of the brackets 77 by a nut 83 at one of its ends and by the curved end 84 adjacent one side of the bracket 85 which is provided with the bore 86 for further supporting one end of the crank shaft 70.

25 The bracket 85 is secured to the bottom wall 8 by the screws 86 which extend through suitable openings in the flange portions 87 of the bracket 85, each of which is disclosed in detail in Figs. 16 and 17.

30 The crank shaft 70 is disclosed in detail in Fig. 25 and is provided with the shouldered portion 88 which may extend through the bore 89 of the rod 90, the shouldered portion 89 being suitably riveted over to provide a pivotal connection between the crank shaft 70 and the rod 90.

35 The rod 90 is disclosed in detail in Figs. 18 and 19.

40 The rod 90 is further provided with the bore 91 at its upper end for forming a pivotal connection at 92 with a latch plate 100 which is adapted to be supported by the rivets or screws 62A, in a manner similar to that disclosed in Figs. 6 and 7, the latch plate 100 being provided with 45 the boss 54 for extending behind and engaging the plunger 93 which is similar to the plunger 24, the plunger 93, however, being provided with an extension portion 94 which extends within and supports one end of the spring or resilient member 95 which is retained at its other end by the recess 96 of the housing 97 which is secured to the outside door 10 by the screws or rivets 28.

50 The plunger 93 is disclosed in its assembled position within the housing 97 in Figs. 14 and 15.

55 Also one of the latch plates 100 is disclosed in Figs. 20, 21 and 22, the latch plate 100 being provided with the arm 98 having a bore 99 therethrough for providing a bearing for the pivotal connection disclosed at 92.

60 The treadle 69 is provided with feet or block members 101 which are suitably secured to the underside of the treadle 69, the feet or block members 101 being constructed of material having resilient characteristics such as rubber or 65 similar material, the feet or block members 101 being adapted to engage the upper surface of the bottom wall 8 to limit the treadle 69 in its maximum downward movement and to provide means for supporting the treadle member 69 while it is 70 supporting one or more of the milk bottles 67 or similar units as disclosed in Figs. 2 and 3.

75 Also, to normally maintain the treadle 69 in its maximum uppermost position as indicated in Fig. 10, the spring or resilient member 102 comprises a plurality of coils which are mounted

around the crank shaft 70 at points adjacent the inside surfaces of the brackets 71, the coils of the spring member 102 being extended to form the arm 103 which engages the upper surface of the bottom wall 8, the spring member 102 having its coils further extended to form the arms 104 which engage the underside of the treadle 69, the resilient characteristics of the coils of the spring 102 tending to always force the arms 104 away or in an opposite direction from the opposite arm 103, thus tending to always maintain the treadle 69 in its maximum uppermost position until the bottles 67 or similar units are placed on the treadle 69 to cause it to pivotally move to its maximum downward position in which the feet or block members 101 will engage the upper surface of the bottom wall 8.

10 In operation, the inmate of the building structure will open the inside door 11 to place empty milk bottles in the chamber 30 from where the empty milk bottles are to be delivered to the milk man or similar delivery man of similar commodities, the inmate of the building structure, however, taking care not to place any empty milk bottles on the treadle 32 as disclosed in Figs. 2 and 3.

15 The milk man or delivery man is then free to open the outside door 10 which will permit the empty milk bottles 68 to be removed from the chamber 30 and to be replaced by full milk bottles, as indicated at 68 in Figs. 2 and 3, the milk man or delivery man taking care also to place a full milk bottle 67 on the treadle 32 as indicated in Figs. 2 and 3 to operate the treadle 32 downwardly from its position, as disclosed in Fig. 4 to a position adjacent the inner surface of the bottom wall 8 which will in turn operate the crank shaft 41 which, together with its operatively connected mechanism, will move the latch member 52 upwardly so that it will extend between the inside surface of the outside door 10 and the catch portion of the plunger 24 as disclosed in Figs. 6 and 7 to automatically lock the outside door 10 against unauthorized or unlawful opening thereof to remove the milk bottles 68 or similar commodities.

20 In a similar way the milk bottles or similar commodities are placed on the treadle 69 which will operate the catch plate 100 to a position between the plunger 93 and the inside surface of the outside door 10 to eliminate unauthorized or unlawful entry into the self locking container A and removal of the full milk bottles 68 or similar commodities therefrom.

25 I claim:

1. In a self locking container for receiving goods in a building structure and provided with an outside door, the combination of a plunger member movably mounted in said outside door, a catch plate movably mounted in said container and adapted to engage said plunger member and to lock said outside door against unauthorized opening, a pair of brackets and each provided with stop bosses, a crankshaft rotatably mounted in said pair of brackets, a treadle pivotally mounted on said crankshaft and adapted to engage said stop bosses of said pair of brackets, said treadle being adapted to be actuated by the placement of said goods thereon, a resilient member provided with coil portions surrounding said crankshaft, said resilient member being provided with arms for engaging said treadle and the floor of said container, and a rod member pivotally connected between said crankshaft and said catch plate.

2. In a self locking container for receiving

goods in a building structure, and provided with an outside door, the combination of a treadle pivotally mounted in said container and adapted to be actuated by the placement of said goods thereon, resilient blocks mounts on said treadle and adapted to engage the floor of said container to support said treadle in its lowermost position, a crankshaft rotatably mounted and supporting said treadle, said crankshaft being provided with

a crank arm, a plunger mounted on said outside door, a catch plate movably mounted and adapted to engage said plunger to lock said outside door against unauthorized opening, said catch plate being provided with a flange, and a rod pivotally connected between said crank arm of said crank-shaft and flange of said catch member. 5

ALBERT ST. ARNAULD.
